UNITED STATES PATENT OFFICE.

SAMUEL JONES, OF TRANMERE, COUNTY OF CHESTER, ENGLAND.

PRINTING BLOCK OR TYPE.

SPECIFICATION forming part of Letters Patent No. 400,087, dated March 26, 1889.

Application filed April 13, 1886. Serial No. 198,744. (No model.) Patented in England August 18, 1885, No. 9,782.

To all whom it may concern:

Be it known that I, SAMUEL JONES, printer, a subject of the Queen of Great Britain, residing at Tranmere, in the county of Chester, 5 in the Kingdom of England, have invented certain new and useful Improvements in Printing Blocks or Type, (for which application has been made in England, dated August 18, 1885, No. 9,782,) of which the following is a specification.

In the printing of large posters it has been usual to cut each letter separately. This is very expensive, the type is very bulky and difficult to store, and in the case of very large 15 letters is liable to injury.

Now, this invention consists in building up the letters from tesseræ or small rectangular types of uniform size, or of multiples of uniform size, so that the same blocks can be used 20 for the different letters of the alphabet and for letters of a variety of sizes. I find that to make the letters of the alphabet either plain sansceriph letters or letters with ceri- 25 phs—white on a black ground or black on a white ground—requires from eleven to fourteen different blocks, and by the use of a few more I can make a considerable variety of fancy or plain type. It is not absolutely necessary that the blocks should be square, as 30 oblong or triangular ones will also answer; but after trying many different arrangements I have found that the system of square blocks with multiples or divisions of square blocks, if desired, is the best.

35 In order to make my invention better understood, I have shown in the drawings the letters A and B compounded of a series of blocks in white and black, and have also drawn these blocks separately and grouped 40 in order the better to explain my system. The parts shown white are spaced with blocks of the same size, with the exception that they are not so high. I have added outlines of the blocks to show their form and what parts are 45 cut away so as to be below type-height. It will be seen that by simply reversing the blocks a black or white letter will be produced. I have shown rather more than fourteen simple blocks, and also combination- 50 blocks wherein two or more pieces are combined into one compound block, so as to make

a very complete set to show a variety of arrangement of letters. Every one of these could be formed out of those numbered 1 to 11, as shown; but I prefer to cut separate 55 blocks for those numbered 12 to 17, as they will be largely required, and the square will be constructed of one block instead of two. When not cut in separate blocks, No. 12 would be constructed of Nos. 9 and 1, No. 13 60 of Nos. 9 and 2, No. 14 of Nos. 9 and 5, No. 15 of Nos. 9 and 6, No. 16 of Nos. 9 and 7, and No. 17 of Nos. 9 and 8. The Nos. 1 2 5 6 7 8 may be cut in blocks of oblong shape, as shown, or be cut out of square blocks in the 65 former case. A block such as No. 9 or its reverse, No. 9', which is below type-height to form a blank, will make up the square. No. 10 may be a separate block, or constructed out of two blocks No. 9. Its reverse, No. 10', 70 will be cut of one or two pieces, as required.

Figures 1 and 4 on Sheet 2 are perspective views of blocks.

To nicely complete the "B," as shown in the drawings, I form the inner rounded corners, a, of the block or type No. 4 from the set or size of type smaller than the one in use and of which the one in use is the multiple. Nos. 18 to 23 show some of the combinations the blocks will assume in forming the letters. 75 Nos. 24 to 31 show combination-blocks, such as may be cut for the formation of special letters, to reduce the number of pieces. The numbers indicate the primary pieces of which they are composed. A few other blocks or 80 types may be found desirable to add fancy turns, comma-tails, and the like.

The blocks can be manufactured from metal, wood, or composition, either cast, molded, or cut to the desired size and shape, and they 90 should be made to fit against each other to a great nicety, the edges perfectly flush, so as to prevent the joints from showing when printed, and to all intents and purposes to have the appearance of a solid block. 95

In conclusion, I am well aware that borders have been constructed or composed of a large number of recurring pieces or type, and also that it has been proposed to form large solid or ornamental surfaces by means of numerous small types in combination grouped together in vast bunches, and I make no claim 100

for such. This proposition had not to my knowledge been carried to a successful pass at the date of my present application, if it has yet, indeed, and these small type had 5 hardly any relation to the shape of the letter or figure made thereby, further than to build it up out of an almost innumerable quantity of small types grouped together, so as to roughly form the letter or figure, while mine o simply divides the letter or figure into the fewest practicable number of pieces, to form it of a few simple types.

I am aware that it has been proposed to construct printing-blocks in sections having 5 geometric figures produced upon their printing-faces, said blocks being capable of and designed for combination in such manner as to produce various ornamental designs, borders, mosaics, and the like, and perhaps, in o cidentally and indifferently, a few letters of the alphabet; and I am further aware that printing-scrolls have been made which might, by careful combination, be made to produce letters of the alphabet. I am not, however, 5 aware that any one has ever before produced a complete series of printing-blocks having geometric forms, which by proper combinations will give all the letters of the alphabet. By my invention this result is attained, and o each and every letter is perfectly formed, a result which can only be secured by a careful study of the formation of all the letters, and by making the printing-faces of the blocks to correspond in size, shape, and curve or in- 5 elination with the sizes, shapes, curves, and angles of the respective letters.

The invention is designed more particularly for the printing of bills, posters, &c., where the expense of cutting out each large letter is not only great, but is attended by 40 considerable labor, and when thus made the types are heavy and unwieldy.

While disclaiming the broad idea of a series of blocks bearing different geometric figures and adapted to be combined to produce 45 printing-surfaces, what I claim is—

1. A series of printing-blocks each having a printing-surface corresponding in form and size to a given portion of a letter of the alphabet, the series embracing one or more 50 blocks corresponding with every part of each and every letter of the alphabet, whereby said blocks are adapted to be combined to produce a printing type or block for every letter of the alphabet.

2. A font of printing-blocks each of a given size or multiple thereof, and each bearing a geometric form corresponding in form and dimensions with a definite part of a letter of the alphabet, the font containing a number of such 60 blocks corresponding with each part of the several letters of the alphabet, whereby they are adapted to produce, when properly combined, each and every letter of the alphabet.

In testimony whereof I have signed my name 65 to this specification in the presence of two subscribing witnesses.

SAMUEL JONES.
